BEARING

Charles A. Ferguson, North East, Md.

Application October 9, 1936, Serial No. 104,877

1 Claim. (Cl. 308—189.)

The device forming the subject matter of this application is a bearing adapted to receive the thrust of a propeller shaft in a boat, and the present application proposes improvements in the structure shown in my former Patent No. 1,990,119, issued on February 5, 1935.

In the case at bar, it is proposed not only to take care of the end thrust, but, as well, to provide a means for supporting, for anti-frictional rotation, the propeller shaft of a water craft, thereby making it possible to turn the propeller shaft at high speed.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, 25 without departing from the spirit of the invention.

In the drawing:

Fig. 1 shows in horizontal longitudinal section, a device constructed in accordance with the invention;

Fig. 2 is a cross section on the line 2—2 of Fig. 1;

Fig. 3 is an end elevation wherein parts have been removed, the shaft appearing in section, and portions being broken away;

Fig. 4 is a plan of the lock washer employed.

In carrying out the invention, there is provided a casing 1 of cylindrical form, the casing being supplied between its upper and lower surfaces with rigid, outstanding, laterally projecting foot plates 2 having openings 3 adapted to receive securing elements (not shown) whereby the foot plates may be secured rigidly to the timbers of a boat. The foot plates 2 are located in a common plane with the axis of the propeller shaft 4, and therefore the thrust of the propeller shaft does not have a tendency to turn over the device fore and aft and thereby put an unnecessary and undesirable upward pull on the securing elements which are mounted in the openings 3.

At its extremities, the casing 1 is provided with inwardly tapered recesses 5, defining shoulders 6 in the casing. The inner portions of the recesses 5 are smooth, the outer portions of the recesses 5 being threaded. First retainers 7 which are hol-

low or cup-shaped, are threaded into the outer ends of the recesses 5 and may be held in place by securing devices, such as set screws 8 threaded into the outer casing 1. The retainers 7 are supplied at their outer ends with wrench heads 9, 5 having internal grooves 52 receiving annular packings 10, which embrace the shaft 4 closely, the shaft extending through the casing from end to end, through the openings 27 in the retainers 7.

The shaft 4 is provided with an enlargement, 10 which may be a collar or sleeve 11, located within the casing 1 and held on the shaft by any suitable means, such as set screws 12 threaded into the casing 1, the set screws being prevented from backing out, because an annular binder 14, preferably a piece of wire, is engaged in the kerfs of the set screws. The collar 11 is equipped with outwardly tapered, reduced ends 15, defining shoulders 16. The reduced ends of the collar or enlargement 11 are supplied with longitudinal 20 slots 17.

Disposed within the first or cup-shaped retainers 7 are second retainers 18 of annular form, which are threaded on the ends 15 of the collar 11, the retainers 18 having seats 50 for the reception of a wrench.

Anti-friction bearings are supplied, and each bearing includes an outer ring 19, an inner ring 20, a cage 21 located between the rings, and balls 22 carried by the cage and located between the 30 rings, the rings having races 23, which receive the balls 22.

When the retainer 18 is advanced, it crowds the inner ring 20 of the ball bearing tightly on the tapered end of the shaft collar or sleeve 11, 35 into abutment with the shoulder 16. The inner ring 20 of the ball bearing, therefore, is securely held upon the shaft collar 11, and consequently connected to the shaft 4 for rotation with the shaft. A lock washer 24, preferably made of 40 metal, is interposed between the second retainer 18 and the inner ring 20 of the ball bearing, the lock washer surrounding the shaft 4. The lock washer 24 has an inwardly extended finger 25, received in the slot 17 of the ends 15 of the enlargement 11 on the shaft 4, the lock washer thus being held on the shaft for rotation therewith. The lock washer 24 is provided with outwardly extended annular resilient fingers 26, which engage the inner ends of the retainer 18 and prevent that retainer from backing off with respect to the inner ring 20 of the ball bearing.

When the retainer 7 is threaded inwardly, it houses the retainer 18, and the outer ring 19 of the ball bearing is forced tightly into the 55

smooth tapered end of the recess 5 of the casing 1, into abutment with the shoulder 6.

It is to be observed that the ball bearings serve two purposes: first, they take up the end thrust; 5 and secondly, they support the shaft 4 for rotation, out of frictional contact with the casing 1 and out of frictional contact with any parts carried thereby, the openings 27 in the retainers 7 being large enough so that there is no frictional 10 drag on the shaft 4, to amount to anything, the friction resulting from the packings 10 being so small that it need not be taken into account. About the shaft enlargement 11, and within the casing 1, there exists a chamber 28 for a lubricant. The lubricant may be introduced through 15 an oil hole 29 in the casing 1, the oil hole being stopped at its outer end by a closure 30, such as a screw threaded into the casing 1. The oil finds its way through the ball bearings, and into the 20 cavities of the cup-shaped retainers 7, the packing rings 10 presenting an exit of oil about the shaft 14. The detailed construction of the article is such that end thrust is accommodated, and at the same time, the shaft 4 is anti-frictionally supported, it being possible to operate the 25

shaft at a much higher speed of rotation than is possible in the device described in my aforesaid Patent No. 1,990,119.

Having thus described the invention, what is claimed is:

In a device for preventing longitudinal movement of the propeller shaft of a boat, a casing having internal shoulders, a propeller shaft provided with an enlargement located within the casing and having tapered ends defining external shoulders; anti-friction bearings comprising outer rings located in the casing and engaging the internal shoulders, inner rings about the reduced ends of the enlargement and engaging the external shoulders, outer cup-shaped retainers 10 threaded into the ends of the casing and binding the outer rings tightly against the internal shoulders of the casing, and inner annular retainers housed within the outer retainers and threaded 15 on the reduced ends of the enlargement, the inner retainers binding the inner rings tightly against the external shoulders of the enlargement of the shaft. 20
